CONVEYER MECHANISM

Harold W. Shonnard, Montclair, N. J.

Application September 16, 1938, Serial No. 230,215

8 Claims. (Cl. 198—151)

This invention relates to improvements in conveyor mechanism.

Its object is to provide a plurality of driven members interconnected by flexible links of wire rope lengths or chains arranged to provide an even rate of movement to the driven members.

Another object is to provide a simple and effective arrangement of the endless belt-sprocket type conveyor in which the belt comprises a plurality of flexible members, and the sprockets and load supporting means are especially designed to cooperate with such a belt.

Another object is to provide an arrangement for adjusting the length of the flexible links to the pitch of the sprockets.

A still further object is to provide a conveyor embodying flexible links which is capable of carrying hot material, such as molten iron, hot coke, etc., without injury to the driving mechanism.

The structure which I am about to describe, as an illustrative embodiment of the invention is a pig casting machine which has these and other novel and useful characteristics which will be pointed out hereinafter.

Referring to the drawings,

Fig. 1 is a side elevation of the upper and lower ends of a pig casting machine which is made according to and embodies my invention;

Fig. 2 is a side elevation on a larger scale of the lower end of the machine illustrated in Fig. 1, showing some of its parts more in detail;

Fig. 2A is a plan view showing two laterally spaced sprockets mounted on a shaft;

Fig. 3 is a view taken at right angles to Fig. 2 of a part of the driving sprocket shown in the latter figure;

Fig. 4 is a plan view of one of the conveyor units shown in Figs. 1 and 2, together with its connected and associated parts;

Fig. 5 is a sectional side elevation of the unit shown in Fig. 4, the section being taken on the line 5—5 of Fig. 4;

Fig. 6 is a front elevation of the parts shown in Fig. 4;

Fig. 7 is a side elevation of the ends of two of the wire rope links;

Fig. 8 is a plan view partly in section of the parts shown in Fig. 7;

Fig. 9 is a view of one of the ropes and its fittings;

Fig. 10 is an end view of a modified form of one of the rope fittings;

Fig. 10A is a sectional side elevation of the fitting shown in Fig. 10; and

Fig. 11 is a side elevation of a modified form of flexible link.

20 designates longitudinally spaced pairs of laterally spaced sprockets mounted on shafts 21, 21A. On the peripheries of the sprockets are two parallel grooves 22, (Fig. 3). At equally spaced intervals transverse pockets 23 are cut across the face of each sprocket to receive tooth members 24 which are removably secured to the sprockets by some suitable means, such as the 10 studs and nuts shown at 25.

The sprockets are connected by an endless belt, one construction of which will be particularly described. 30 designates wire rope lengths of substantially equal dimensions. Collars 31 are swaged or otherwise affixed to the ends of these rope lengths. 32 are externally threaded bushings slipped onto the rope lengths before the collars 31 are applied. These, as shown, have hexagonal flanges 33. 34, 34 are shackles, each having a recess 35 into which one of the collars 31 fits and an internally threaded bore 36 for receiving one of the bushings 32. Spring washers 37 are inserted in the recesses 35 under the collars 31. The part of each shackle on one side of the recess 35 and bore 36 is split, as shown at 38, and arranged to be tightened against bushing 32 when the latter is in its finally adjusted position by a bolt 38A.

Each shackle has an eye 39. The eyes of the outside shackles, as viewed in Fig. 8, are pivoted on a collar 40 which in turn is pivoted on a bushing 41 having a central bore 42 and a head 43. Outside the collar 40 is a collar 44 on which the eyes 39A, 39A of the inside shackles are pivoted. The sprocket teeth 24 engage the part of collar 44 which is between the shackle eyes 39A, 39A. The shackle eyes are offset from the axes of the recesses 35 and bores 36 so that when assembled as shown in Fig. 8 the axes of the recesses 35 of the outside shackles are in the same planes as the axes of the recesses of the inside shackles.

The rope lengths are such as to make the distance between the collars 44 the same as the peripheral distances between the teeth 24 on the sprockets.

In the flexible links shown in Fig. 11, the shackles 34, 34 are connected by a chain 30A.

It is obvious that when an endless belt constructed as thus described, is assembled on two spaced sprockets, as shown in Fig. 1, an operative structure is formed by which either sprocket can be driven by the other through the belt

comprising flexible links, or both sprockets may be used to drive the endless belt.

The length of each link 30, together with its pair of shackles 34 may be adjusted accurately and positively by turning the threaded collars 32. The spring washers 37 facilitate this adjustment in one direction as they tend to push the collars 31 outwardly against the bushings 32.

When the links comprise wire rope, the adjusting bushing 32A shown in Figs. 10, 10A may be constructed with a longitudinal slot 32B of sufficient width to clear the diameter of the rope. Such adjusting collars may be placed on the rope lengths after the collars 31 are applied to them.

The driving mechanism thus described is adaptable to many uses. A structure to which it is particularly adaptable,—a pig casting machine, will now be described.

On each of the shafts 21, 21A a pair of spaced sprockets are provided with their teeth 24 in angular alinement. Two endless belts are likewise provided.

50 designates transverse rods which fit the bores 42 of opposite bushings 41 and are keyed against rotation to prevent wear between the rods and the bushings. 51 are brackets, the front ends 52 of which are pivotally supported on the rods 50. From their ends to the parts which pass through the front ends of the brackets 51, the rods 50 are circular in cross section, but between opposite brackets 51 they are square in cross section, as shown at 53. 54 are short rigid links affixed to the squared parts of the rods 50 and interconnected by cross rods 55 on which the rear ends 56 of the brackets 51 are supported. On the outer ends of the rods 50 are flanged wheels 57 arranged to run on tracks 58 on the upward movement of the conveyer and on tracks 59 on the downward movement of the conveyer, (see Figs. 1 and 2).

60 are conveyer buckets, in this case pig casting molds, four being shown affixed to each pair of side brackets 51. A way of affixing these buckets to the side brackets 51 is illustrated in Figs. 4 and 6, in which 61 designates flanges projecting from the ends of the buckets, fastened by bolts 62 to angle brackets 63. These in turn are secured by bolts 64 to uprights 65 on the side brackets 51 which raise the buckets above the level of the rope links.

Each pair of side brackets with the buckets affixed to them as described forms a rigid unit and these units are hinged together so that they form a train which is inflexible in one plane, but is free to articulate as it passes around the sprockets. Herein is one of the advantages of the structure as it maintains the shafts 50 in parallelism with the axes of the sprockets.

When the apparatus is used as a pig casting machine, molten metal is poured into the buckets 60 at a station indicated by the arrow A in Fig. 1, where the tops of the buckets are level. The shaft 21A is higher than the shaft 21 and sufficiently spaced therefrom to give the metal time to solidify before the buckets reach the upper sprocket. As the units pass around the upper sprocket they are tilted and finally inverted to dump the solidified metal.

The structure shown and described is particularly adapted to withstand the heat to which it is subjected. The heat imparted to the buckets is conducted to the side brackets 51 and through them and the rods 52 and 55 to the shackles 34. The latter are remote from the source of heat, some of which is transmitted to

them through the arrangement of sleeves and bushings illustrated in Fig. 8, which is especially designed to withstand the heat to which it is subjected and which is so arranged that its parts may be easily and quickly replaced when necessary. The buckets are spaced above the wire rope links to minimize the effect of radiation.

It is desirable to impart a uniform movement to the buckets. This is accomplished by the structure described in the following manner: 10 The tracks 59 extend from points to the left of the shaft 21A (Fig. 1) to points to the right of the shaft 21 (Figs. 1 and 2). This causes the axes of the bushings 44 to move in a path tangential to the peripheries of the sprockets and insures the proper engagement of the bushings and the sprocket teeth 24. As the bushings are moved around the sprocket wheels, the rope lengths 30 become seated in the grooves 22. The peripheral distance between two bushings in adjacent sprocket teeth remains, therefore, substantially the same as the distance between adjacent bushings when they are guided in straight lines. As the flexible links operate substantially on the pitch line of the sprocket wheels the train of molds will be propelled at a nearly constant radial and linear velocity.

20 The chordal distance between bushings in adjacent sprocket wheels is considerably shorter and it is to compensate for this difference between the peripheral and chordal distances between adjacent bushings in the sprocket teeth that the mechanism shown has been devised, thereby providing a positive support for each unit at both of its ends. Shortening the distance between adjacent bushings as the belt passes around the sprockets causes the links 54 to rock about the axes of the rods 50. Because the links 54 are affixed to the squared portions 53 of these rods, the rocking movement of the two links on each rod will be equal so that the alinement of the units of the train will be maintained. The lateral rigidity of this hinged arrangement may be further increased by making non-rotative connections between the upper ends of the links 54 and the rods 55.

30 The lower ends of tracks 58 extend beyond the points at which the tangential movement of the bushings 44 begins as they leave the lower sprocket wheel. As the flexible parts of the links 50 straighten out the rigid links 54 rock back to their initial positions.

35 The driving mechanism herein shown and described is, of course, applicable to various kinds and types of conveyers. It is also obvious that when it is used as a part of an endless belt conveyer, the latter may be arranged to carry different kinds of material. The specific conveyer shown is arranged to carry hot material, particularly molten metal, and the parts of the driving mechanism are especially designed to withstand the heat of such transported material, consequently the apparatus is well adapted to carry other hot material, such as hot coke, for example, by simply changing the shape of the 40 material receptacles. In fact, many variations and modifications of construction may be made within the spirit and scope of this invention, and I intend no limitations other than those imposed by the appended claims.

45 What I claim is:

50 1. Conveyer mechanism comprising longitudinally spaced pairs of laterally spaced sprockets, rails intermediate the longitudinally spaced sprockets, transverse rods supported on the rails, 55

5 a plurality of rigid carrying members supported on said rods, each of said carrying members comprising a pair of side brackets and a plurality of transverse molds affixed to said brackets, there being a direct pivotal connection between one end of each bracket and one of the transverse rods and rigid links between the other end of the side brackets and the next adjacent transverse rod, and a series of flexible links, each link
 10 comprising a pair of pivotal shackles and an interconnecting flexible element, said rods passing through the shackles and interconnecting the flexible links, said sprockets having arcuate supports for the flexible elements and one of the laterally spaced sprockets being arranged to drive the rods.

2. In a conveyer structure, an endless belt comprising a series of flexible links, each link comprising a pair of pivotal shackles and an interconnecting flexible element, means pivotally interconnecting the shackles of adjacent links, and means for adjusting the length of each link independently, said means comprising a collar securely affixed to one end of each of the flexible elements, a threaded boss on one of each pair of shackles and a threaded adjusting member on each of the flexible elements to engage the threaded boss on the shackle, whereby the longitudinal distances between all shackles in the belt may be equalized.

3. Conveyer mechanism comprising longitudinally spaced pairs of transverse rods, stiff transversely spaced links rigidly interconnecting the rods of each pair, transversely spaced rigid side members with their opposite ends pivoted to differently positioned rods of adjacent pairs, and flexible links interconnecting like positioned rods of adjacent pairs to form an endless belt.

4. Conveyer mechanism comprising longitudinally spaced pairs of transverse rods, stiff transversely spaced links rigidly interconnecting the rods of each pair, transversely spaced rigid side members with their opposite ends pivoted to differently positioned rods of adjacent pairs, one rod of each pair extending beyond the side members, and flexible links connected to the extended ends of said rods to form an endless belt.

5. Conveyer mechanism comprising longitudinally spaced pairs of laterally spaced sprockets, longitudinally spaced pairs of transverse rods, stiff transversely spaced links rigidly interconnecting the rods of each pair, transversely spaced rigid side members with their opposite ends pivoted to differently positioned rods of adjacent pairs, flexible links interconnecting like positioned rods of adjacent pairs to form an endless belt, and sprocket wheels adapted to support the flexible links, one of the sprocket wheels having teeth arranged to drive said belt.

6. Conveyer mechanism comprising longitudinally spaced pairs of laterally spaced sprockets, longitudinally spaced pairs of transverse rods, stiff transversely spaced links rigidly interconnecting the rods of each pair, transversely spaced rigid side members with their opposite ends piv-

oted to differently positioned rods of adjacent pairs, flexible links interconnecting like positioned rods of adjacent pairs, each link comprising a pair of pivotal shackles and an interconnecting flexible element, said links forming an endless belt, said sprockets having arcuate supports for the flexible elements, one of the sprockets having teeth arranged to drive the belt, and wheels on like positioned rods of each pair arranged to support said rods.

7. Conveyer mechanism comprising longitudinally spaced pairs of laterally spaced sprockets, longitudinally spaced pairs of transverse rods, stiff transversely spaced links rigidly interconnecting the rods of each pair, transversely spaced rigid side members with their opposite ends pivoted to differently positioned rods of adjacent pairs, flexible links interconnecting like positioned rods of each pair, each link comprising a pair of pivotal shackles and an interconnecting flexible element, said like positioned rods passing through the shackles and interconnecting the links to form an endless belt, said sprockets having arcuate supports for the flexible elements, one of the sprockets having teeth arranged to drive said belt, wheels on like positioned rods of each pair, rails arranged to support the said wheels, and means for adjusting the length of each link independently, said means comprising a collar securely affixed to one end of each of the flexible elements, a threaded boss on one of each pair of shackles and a threaded adjusting member on each of the flexible elements to engage the threaded boss on the shackle, whereby the longitudinal distances between all shackles in the belt may be equalized.

8. Conveyer mechanism comprising longitudinally spaced pairs of laterally spaced sprockets, longitudinally spaced pairs of transverse rods, stiff transversely spaced links rigidly interconnecting the rods of each pair, transversely spaced rigid side members with their opposite ends pivoted to differently positioned rods of adjacent pairs, one rod of each pair extending beyond the side members, flexible links near the extended ends of said rods, each link comprising a pair of pivotal shackles and an interconnecting flexible element, said extended rods passing through the shackles and interconnecting the links to form an endless belt, said sprockets having arcuate supports for the flexible elements, one of the sprockets having teeth arranged to drive said belt, wheels on the extended ends of said rods, rails arranged to support the said wheels, and means for adjusting the length of each link independently, said means comprising a collar securely affixed to one end of each of the flexible elements, a threaded boss on one of each pair of shackles and a threaded adjusting member on each of the flexible elements to engage the threaded boss on the shackle, whereby the longitudinal distances between all shackles in the belt may be equalized.
